PUMP.

SPECIFICATION forming part of Letters Patent No. 759,145, dated May 3, 1904.

Application filed September 12, 1900. Serial No. 29,841. (No model.)

To all whom it may concern:

Be it known that I, PERRY M. WING, a citizen of the United States, residing at Boyd, in the county of Wasco and State of Oregon, have 5 invented a new and useful Pump, of which the following is a specification.

This invention relates to pumps in general, and more particularly to the class of force-pumps, and it has specific reference to double-cylinder pumps, the object of the invention being to provide a pump wherein the water will be forced from the cylinders by the displacing action of plunger-rods passed into the cylinders and out of contact with the inner 15 surfaces of the latter. The result of this construction is that there is a minimum of friction in the pump, and the reasons for the low friction are the lubricating action of the liquid which wets the rods of the pump and 20 the fact that the rods have frictional contact only with the packing of the stuffing-boxes.

In the drawings forming a portion of this specification, and in which like numerals of reference indicate similar parts in the several 25 views, Figure 1 is a plan view showing the complete pump. Fig. 2 is a vertical section taken longitudinally through the pumping-cylinders and showing the plunger in elevation. Fig. 3 is a section on line 3-3 of Fig. 1.

Referring now to the drawings, the present 30 pump comprises two cylinders 5 and 6, having equal areas and which are disposed in axial alinement and separated by an interspace, the mutually adjacent ends of the cylinders being 35 provided with adjustable stuffing-boxes 7 and 8, as shown, the diameters of the openings through the outer ends of the caps of the boxes being somewhat less than the interior diameters of the cylinders.

A common plunger is provided for the two 40 cylinders, and this common plunger consists of a piece of cylindrical shafting 9, having a diameter to fit snugly in the openings in the outer ends of the caps of the stuffing-boxes, 45 so that the ends of the plunger, which enter the pumping-cylinders, lie close to but do not touch the inner surfaces of the cylinders. Thus as the plunger is reciprocated it will

move inwardly of one cylinder and outwardly of the other, effecting a discharge from one 50 cylinder by displacement and causing suction in the opposing cylinder by withdrawal of its bulk therefrom. By thus forming the plunger so as to lie out of contact with the inner faces of the pumping-cylinder friction there- 55 between is prevented, and the only friction to be overcome is that between the plunger-rod and the stuffing in the stuffing-boxes, the stuff- ing or packing of the boxes being shown at 10.

At the base of each pumping-cylinder 5 and 6 there is connected a three-way connection or T 11, the heads thereof lying in a common plane, and with one pair of corresponding ends of the heads are connected inlet-pipes, while with the opposite ends of the heads are connected the exhaust-pipes.

The supply-pipes include each a check-valve 12, connected directly to the head of a connection 11 and opening in the direction of its respective pump-cylinder, the opposite ends of 70 the casings of the check-valves being connected by suitable piping 14^a with a suction-pipe 14, as shown.

With the opposite ends of the heads of the three-way connections 11 are connected the 75 casings of check-valves 15, which valves open away from the pump-cylinders, said casings having the exhaust-pipes 16 connected therewith and leading to a common exhaust pipe or main 17.

The supply-piping 14^a and the discharge-piping 16^a are each provided with a T 14^b and 80 16^b, whereby connection is made with the suction-pipe 14 and the exhaust-pipe 17, as will be readily seen, and each of said pipings 14^a 85 and 16^a are also provided at one side of the T with unions 14^c and 16^c, whereby the members or sections of said pipings may be connected in the act of assembling the parts of the pump for operation. With this construc- 90 tion it will be seen that as the plunger-rod is moved in one direction one inlet check-valve 12 will open to admit water to its cylinder, while the other inlet check-valve will close to prevent back pressure of water therethrough 95 from its cylinder. At the same time the out-

let check-valve of the first cylinder will close to prevent return of water therethrough from the exhaust-pipe, and the outlet check-valve of the second cylinder will open to permit 5 water to be forced from its cylinder through the exhaust-pipe. When the plunger is moved in the opposite direction, the valves are reversely operated and the functions of the cylinders are reversed. This operation is well 10 understood by those skilled in the art.

In order to operate the plunger-rod 9, a lug 18 is formed thereon or secured thereto at a point between the ends of the cylinders 5 and 6, and with this lug is connected a reciprocating rod 19, the end portions of which have 15 bearings in perforations 20, formed in upwardly-projecting lugs 21 upon the three-way connections 11, one end of this rod 19 being adapted for connection with an operating 20 means, as shown.

It will be seen from the foregoing that my improved pump is of an extremely simple construction, consisting practically of nothing but piping of the most ordinary kind, with the 25 various joints—such as T's, L's, unions, and valves—of the most ordinary construction, which, however, have been assembled in such a manner as to produce a most satisfactory pump at a very trifling expense. Practically 30 the only special construction required by my invention is that of the two T's, which are provided with upwardly-extending lugs 21, having perforations 20 for the passage of the operating-rod. The pump and cylinder are nothing 35 but an ordinary piece of shafting having an upwardly-extending lug, with which the operating-rod is connected, said operating-rod extending through the bearings in the upwardly-extending lugs of the T's. It is in order to permit 40 these parts to be conveniently assembled or taken apart that the unions 14^c and 16^c are provided, and it will be seen that by simply removing these unions the pump may with the greatest facility be disassembled, if it should be 45 found necessary, for cleaning or other purposes. The plunger is not in contact, and it is not intended to be in contact with the walls of the cylinder, this being avoided by the use of

the packing-boxes at the ends of the cylinders. The absence of friction resulting from this construction greatly facilitates the operation of the device, the ordinary pistons being entirely dispensed with. 50

What is claimed is—

1. A pump comprising a pair of T's having 55 upwardly-extending lugs, supply and exhaust pipes connected with said T's and including check-valves, a suction-pipe connected by a T with the supply-piping, a discharge-pipe connected by a T with the exhaust-piping, unions 60 connecting the members of the supply and exhaust pipings whereby the frame including the latter may be readily disassembled, cylinders connected with the T's having the upwardly-extending lugs, a reciprocating plunger 65 engaging said cylinders and having an upwardly-extending lug, and an operating-rod engaging said lug and extending through bearings in the lugs extending upwardly from the T's. 70

2. A pump of the class described comprising 75 a pair of cylinders disposed in axial alignment, stuffing-boxes on the opposing ends of the cylinders, T-joints at the outer ends of said cylinders, having perforated lugs formed thereon, casings containing check-valves connected with the ends of the T-joints, elbows connected with said casings, pipes connecting the opposing ends of said elbows, said pipes including T-joints for the admission 80 and expulsion of water, and unions whereby the pump structure may be disassembled, a reciprocating solid cylindrical plunger 85 extending through the stuffing-boxes into the cylinders and of less diameter than the latter, a plunger-rod having rigid connection with the plunger and extending through the bearings formed by the perforated lugs upon the T-joints at the outer ends of the cylinders. 90

In testimony that I claim the foregoing as my own I have hereto affixed my signature in the presence of two witnesses.

PERRY M. WING.
